UNITED STATES PATENT OFFICE.

FRANK G. BAUM, OF STANFORD UNIVERSITY, CALIFORNIA, ASSIGNOR TO STANLEY ELECTRIC MANUFACTURING COMPANY, OF PITTSFIELD, MASSACHUSETTS, A CORPORATION OF NEW JERSEY.

MEANS FOR COMPENSATING GENERATORS OR MOTORS.

SPECIFICATION forming part of Letters Patent No. 698,245, dated April 22, 1902.

Application filed September 5, 1901. Serial No. 74,374. (No model.)

To all whom it may concern:

Be it known that I, FRANK G. BAUM, a citizen of the United States, residing at Stanford University, California, have invented certain new and useful Improvements in Means for Compensating Generators or Motors, of which the following is a full, clear, and exact description.

My invention relates to the compensation of generators and motors, and has for its object to produce a more efficient and simple means for accomplishing such compensation and one which is more easily manipulated than those heretofore used.

15 In carrying out my invention in connection with generators I employ an auxiliary machine which supplies the whole or part of the exciting-current of the main generators. This machine runs at a substantially constant speed and is energized by the current in the main circuit so as to respond to changes in the load carried by the main generators and more highly energize the main-generator field-magnets as the load increases.

20 25 The following is a description of my invention, reference being had to the accompanying drawings, in which—

Figure 1 represents diagrammatically one embodiment of my invention, and Fig. 2 is a 30 modification of the same.

Referring to the drawings, A A' are two continuous-current generators in parallel, B B' being the armatures, C C' the field-energizing coils, D D' the mains, and L L the lamps 35 or other translating devices constituting the load on the system.

E is an auxiliary generator or compensator running at a constant speed and having a shunt-winding F and an additional winding G in series with the load L. From the brushes of this compensator are two leads H H', which supply the energizing-coils C C' of the main generators A A', the coils C C' being in parallel across the compensator-leads. It will be seen that in the above arrangement as the load increases and the potential along the line tends to fall the increase of current in the coil G increases the compensator electromotive force and the current in the energiz-

ing-coils C C', which in turn increases the 50 magnetism of the main-generator field-magnet and counteracts any tendency toward a drop in potential along the lines due to the increase of load. This system of compensation simplifies the construction of the generators and where two or more generators are installed has very substantial advantages since by the simple addition of the compensator 55 the generators may be made with a single winding and the need of all equalizer connections is done away with, also the adjustment of low-resistance shunts, which must otherwise be made to make all machines take 60 their proper proportion of the load. Moreover, with this arrangement there is no drop 65 in potential when a new machine is added to one or more already running.

In the modification shown in Fig. 2 instead of compounding the compensator the energizing-coil on the main generators is connected in shunt to the armature, and the shunt-coil is omitted from the compensator field-magnet. In this arrangement the shunt-coil 70 of the main generator has a varying difference of potential due to the compensator impressed upon its terminals, thereby compensating for any tendency toward change in potential due to change in load.

Referring more particularly to Fig. 2, M M' are the main generators. N N' are the armatures connected to the mains O O'. P P' are the energizing-coils of the main generators. Q is the compensator having its field-magnet coil R in series with the load L and impressing an electromotive force on the energizing- 85 coils P P' which increases as the load on the system increases and results in proper variation in the magnetization of the main field-magnets.

What I claim is—

1. In a system of distribution, the combination of a plurality of dynamo-electric machines having but one energizing-winding on each of their field-magnets, and an auxiliary dynamo-electric machine in circuit with the 90 field-magnet windings and having an energizing-coil in series with the armature-circuits of the main dynamo-electric machines.

2. In a system of distribution, the combination of a plurality of generators in multiple arc having their energizing-coils in multiple arc and an auxiliary generator having a field-
5 magnet coil in series with the load on the system and supplying energy to the energizing-coils of the main generators.

Signed at Butte, Montana, this 29th day of July, 1901.

FRANK G. BAUM.
